STEREOSCOPIC CAMERA

Wilhelm Witt and Albert Beck, Hamburg, Germany

Application March 7, 1955, Serial No. 34,894

Term of patent 3½ years

(Cl. D61—1)

Fig. 5

Fig. 4

Fig. 1

Fig. 3

Fig. 2

Fig. 6

Fig. 1 is a front elevational view of a stereoscopic camera embodying our new design;

Fig. 2 is a top plan view thereof;

Fig. 3 is a side elevational view seen from the left side of Fig. 1;

Fig. 4 is a side elevational view seen from the right side of Fig. 1;

Fig. 5 is a bottom plan view thereof; and

Fig. 6 is a rear elevational view.

We claim:

The ornamental design for a stereoscopic camera, substantially as shown.
